UNITED STATES PATENT OFFICE.

MYER L. VICTORIUS, OF NEW YORK, N. Y.

LOOPER FOR HOSIERY.

Application filed December 14, 1923. Serial No. 680,618.

This invention relates to an improvement in loopers for closing the open toe of stockings as they come from the knitting machine.

As is well known in the manufacture of stockings, especially those knit on circular machines, the stockings as they come from the knitting machine have an opening at the toe which must be closed.

The closing of the opening in the toe is effected by means of a device known as a looper, the stocking being provided with a looper round, or superfluous fabric, to afford a handhold for the operator and enable the loops which are to be looped together to be engaged with the points on the looper.

When the loops to be formed together to close the toe are engaged with the looper points, the surplus fabric or looper round is cut off close to the looper points, either by shearing means attached to the machine or by hand shears. After the surplus fabric is cut off, there are retained, by the loops on the looper points, thread ends or ravelings of the cut loops, which, if not removed, would be interlocked with the stitching when the loops on the points are joined to each other, with the result that an irregular welted or heavy seam would be formed.

In the earlier loopers, these thread ends or ravelings were removed by hand and later by means of a brush.

In a patent issued to me January 6, 1925, No. 1,522,348, there is disclosed an improved form of brush device for removing the thread ends, wherein the brush is so mounted and actuated as to be automatically and continuously cleared of lint and thread ends so that a substantially clean brushing surface is always presented and further while the brush is so actuated that the bristles around the entire brush will be subjected to the same wear, thus maintaining all the bristles at substantially the same length.

Now the object of my invention is to provide a brush device for loopers, which will embody in improved form the advantageous features of my above mentioned application and which will be capable of very fine adjustment, thus insuring the maximum efficiency in operation, ready compensation for wear, and increased life.

A further object is to provide the device with novel shield and guard structure which will afford great protection to the looper from lint thrown by the brush device.

Having now indicated, in a general way, the

nature, purpose and advantage of my invention, I will proceed to a detailed description of a preferred embodiment thereof, with reference to the accompanying drawings, in which—

Fig. 1 is a plan view, partially in section, of a looper brush device embodying my invention.

Fig. 2 is a cross-sectional view on line 2—2 Fig. 1 showing a portion of the subject of Fig. 1.

Fig. 3 is an elevation of the subject of Fig. 1 looking at the left hand side.

Figs. 4 and 5 are views showing details of construction.

Fig. 6 is an elevational view showing arrangements of guards, with the looper brush device indicated therein.

Fig. 7 is a detailed view showing a portion of the upper guard and rotating table of the looper.

a designates a supporting bracket on which is adjustably mounted a vertical rod *b* held in adjusted position by means of a clamp screw *a'* in cooperation with jaws *a''*, one of which is in threaded engagement with screw *a'* while the other is sleeved thereon. Rod *b* is provided near its lower end with a boss *c* adjacent the upper face of the bracket *a* and a boss *d* adjacent its upper end. The boss *c* is extended at one side to form a housing and drilled for the passage of an adjusting screw *z* which engages in a threaded hole in the supporting bracket *a* and enables a fine adjustment of the vertical rod *b* in reference to the bracket *a*. The boss *d* is drilled for the reception of an end of an angle bracket *e* secured thereto by a nut *e'* and provided with a boss *f* adjacent its end which is mortised as at *g* with boss *d*. The opposite end of the angle bracket *e* is drilled and tapped for the reception of a threaded bushing *h* and split and provided with a clamping bolt *i* for the purpose of clamping the bushing in any adjusted position. The angle bracket *e* with the vertical rod *b* forms an inverted U-shaped support and serves to support a shaft *j*, one end of which passes through boss *c* and is held by a nut *k* while the other end reduced as at *j'* passes through bushing *h*.

Mounted for movement on the shaft *j* is a raveling brush *l* provided with a wooden hub affording a friction surface *m*. Adjacent the brush is mounted for oscillation on shaft *j* a disc *n* having a leather facing *o* and provided with a hub *p*. The leather facing *o* is

normally held in driving relation with the friction surface m of the brush by a compression spring q , the tension of which, and hence the friction between the friction surface m and the facing o of disc n , may be adjusted by means of a nut r and lock nut r' threaded on the shaft.

The hub p is provided with a cut-away portion s having a cam surface t therein, which is arranged to coact with a fixed pin u extending from shaft j into the cut-away portion.

Secured to shaft j , as a center, adjacent the end of bracket e , is a segment v provided with an arcuate slot w . A bolt x is adapted to pass through the slot w , through a bushing y threaded into bracket e and clamp the segment in adjusted position.

Passing through the boss f , as a support, and held thereto by means of a set screw 1 , is a curved bracket 2 , which supports, at its lower end, a comb 3 adapted to act on the brush, as shown in Fig. 2.

The brush is actuated by means of a bell crank lever 4 , the long arm of which is connected to the disc n by means of an adjustable link 5 ; the connection between the link and disc by means of a ball and socket joint 6 giving a universal motion. The short arm 30 of the bell crank is connected to the looper actuating mechanism in any convenient manner, not shown, by which the bell crank is given a reciprocating motion.

In adjusting the device for operation, it is desirable that the link 5 travel as nearly as possible parallel to the brush and to accomplish this, the mechanism is adjusted about support b so that the angle of throw of link 5 will be split. In the movement of the mechanism for this purpose, it becomes necessary to vary the lengths of link 5 , which, for this purpose, is made adjustable.

Pivoted as at 7 to an extension 8 of the support a is a box-like guard member 16 adapted to lie over the looper brush device, as shown in Fig. 6, and prevent the thread ends and lint brushed out from flying into the mechanism of the looper. To the lower edge of the inner wall of this guard is adjustably secured, by means of bolts 11 extending through slots in the wall of the guard, a strip of felt 10 , the lower edge of which is cut out to clear the looper point 14 , as shown in Fig. 7, and extends below the edge of the guard and is adapted to bear on the rotating table 12 of the looper and act to support the guard, at the same time preventing the passage of any lint between the guard and rotating base of the looper. A stop 9 is positioned at the end of the extension 8 of the support a and is adapted to support the guard 16 when it is turned on its pivot 7 out of cooperating relation with the brush device, as indicated in Fig. 6.

Secured to the extension 8 of the support

a and depending therefrom is a skirt guard 13 .

In the operation of the device, the bell crank 4 is continuously oscillated by the looper actuating mechanism and the material to be looped is placed on the points in advance of the shears, not shown. As the placed fabric passes the shears, the surplus material or looper round is cut from above the loops on the points as is customary. The points with the loops thereon and the loose ends hanging thereto are passed under the brush after passing the shears in a step-by-step manner well known in the art. The brush is oscillated through the medium of link 5 to brush the loose threads from the loops on the points. The pressure of spring q is adjusted so as to cause the brush l to move with disc n when the disc and brush are in engagement with each other. As the device is illustrated in Fig. 2, the brush and disc are being moved clockwise and will be so moved until the cam surface t rides under pin u for a short distance. As the cam surface t rides under the pin u and as the pin reaches the end of the cam surface (see Fig. 1), the disc n will be withdrawn from the brush l so that said brush will be free to move independently of said disc. When disc n is drawn from friction surface m , the momentum of the brush will cause the brush to continue its clockwise movement for a short distance before the disc and brush are re-engaged by the spring q permitted to act by the release of pin u from cam surface t in the counter-clockwise movement of the disc.

In the counter-clockwise movement of disc n , it will be forced against friction surface m after the cam surface t leaves pin u and will move the brush during its full return stroke (counter-clockwise) after engagement of the friction surface. It will, therefore, be seen that for each reciprocation of the mechanism, the brush will become separated, at the end of the stroke of the link 5 toward the right, from its driving disc n , and the momentum of said brush will cause it to rotate independently of its disc in a clockwise direction. Thus, when the brush is again engaged by the disc and is caused to move as a unit with said disc, the position of the brush with respect to said disc will have changed so that a clean brushing surface will be presented to the fabric. As the brush is turned clockwise about its axis, in a step-by-step manner about the same distance for each complete reciprocation, the brush is not only continuously cleaned, but its regular and continuous advance provides that all of the bristles will be subjected to substantially the same wear, so that the length of the bristles will all be maintained substantially the same over the entire brush regardless of the wear to which the brush is subjected.

After use, the bristles of the brush l become

shorter as a result of wear, and it becomes necessary to adjust the brush toward the work. This adjustment must be made very accurately and is accomplished by loosening the 5 clamping screw α' and turning the adjusting screw ε , which acts to draw rod b and bracket e down or up, as the case may be, with the result that the brush is moved to or from the work. By virtue of the adjusting screw, the 10 rod b may be adjusted with a high degree of fineness, resulting in a nice adjustment of the brush, which is maintained by tightening up the clamping screw α' .

It is necessary that the cam surface t and 15 the pin u on shaft j be so adjusted in relation with each other that the disc n , which is reciprocated with a constant stroke, be engaged and released from driving relation with the friction surface m of brush l at the proper 20 time in order that the brush in its reciprocation may have the proper clockwise and counter-clockwise strokes to properly do its work and at the same time have the desired step-by-step rotative movement independently of 25 its driving means. It is also desirable that the pin shall not ride against the wall of the cut-out portion of the hub of disc n before the cam surface t is reached. To effect the proper adjustment of the release and engagement 30 of the disc and brush, the pin u may be adjusted relative to the cam surface t by turning the shaft j relative to the hub of disc n through the medium of segment v , which, when the proper adjustment is made, is clamped in position 35 by means of clamping bolt α .

The pin u may be adjusted clear of the wall of the cut-out portion of the hub by adjusting the shaft j longitudinally through the medium of bushing h which, when threaded in or out 40 of bracket e , acts to move the shaft longitudinally with reference to the hub of disc n .

When shaft j is moved longitudinally, segment v moves with it and the clamping bolt α is adjusted to conform to increased or decreased 45 distance of the segment from bracket e .

By virtue of the arrangement of the guards, the guards and the brush assembly are unitary

and may be removed and applied to the looper as a unit. At the same time, the box guard is 50 partially supported by the rotating base of the looper and the looper mechanism is thoroughly protected from lint.

Having now fully described my invention, what I claim and desire to protect by Letters 55 Patent is:

1. In a thread end removing device for looping machines, a support adapted to be connected to the looping machine, a brush carried by the support, a comb carried by the 60 support and in engagement with the brush, means for oscillating the brush, a guard pivotally secured to the support and adapted to overlie the brush, and means carried by the guard and adapted to bear on the rotating 65 table of the looping machine whereby the guard will be supported.

2. In a thread end removing device for looping machines, a support adapted to be connected to the looping machine, a brush carried by the 70 support, a comb carried by the support and in engagement with the brush, means for oscillating the brush, a box-like guard pivotally secured to the support and adapted to overlie the brush, and a strip of 75 felt adjustably secured adjacent an edge of the guard and adapted to bear on the rotating table of the looping machine whereby the guard will be supported.

3. In a thread end removing device for 80 looping machines, a support adapted to be connected to the looping machine, a brush carried by the support, a comb carried by the support in engagement with the brush, means for oscillating the brush, a guard pivotally secured to the support and adapted to overlie the brush, means carried by the guard and adapted to bear on the rotating table of 85 the looping machine whereby the guard will be supported, and a skirt guard secured to 90 and depending from said support.

In testimony of which invention, I have hereunto set my hand, at New York, on this 12th day of December, 1923.

MYER L. VICTORIUS.
